UNITED STATES PATENT OFFICE.

GAYLORD W. BEEBE, OF CLAYTON, GEORGIA.

TOOTH-BRUSH.

1,197,174.

Specification of Letters Patent. Patented Sept. 5, 1916.

Application filed November 5, 1913. Serial No. 799,295.

To all whom it may concern:

Be it known that I, GAYLORD W. BEEBE, a citizen of the United States, and resident of Clayton, Rabun county, Georgia, have invented certain new and useful Improvements in Tooth-Brushes, of which the following is a specification.

In tooth brushes, as usually constructed, the bristles are mounted in an extension of 10 the handle forming the back of the brush and in using, become unevenly worn, those at the outer end or toe of the brush usually wearing away faster than the bristles at the heel of the brush, and this uneven wearing 15 of the bristles causes an unequal pressure on the teeth and imperfect brushing thereof. It is frequently necessary therefore, to throw away a brush which may be considerably worn at one point and in perfect condition 20 for use at other points. It also sometimes happens that some of the bristles will work loose in the head, necessitating the throwing away of the entire brush.

The object of my invention is to provide a 25 tooth brush handle having a detachable or removable brush head, which can be removed, and a new head substituted therefor when desired.

A further object is to provide a brush 30 head that is capable of reversal on the handle to permit uniform wear of the bristles from end to end of the brush.

My invention consists generally in various 35 constructions and combinations, all as hereinafter described and particularly pointed out in the claims.

In the accompanying drawings forming part of this specification, Figure 1 is a side view of a tooth brush embodying my invention, Fig. 2 is a plan view of the head portion of the brush, Fig. 3 is a transverse, sectional view on the line $x-x$ of Fig. 1, Fig. 4 is a sectional view of the brush head, illustrating a modified construction, Fig. 5 is a 45 transverse, sectional view on the line $y-y$ of Fig. 4, Fig. 6 is a detail, sectional view of the brush head showing another modification, Fig. 7 is a plan view of the same, Fig. 8 is a transverse, sectional view on the 50 line $z-z$ of Fig. 7, Fig. 9 is a side view of the brush head, illustrating still another modification, Fig. 10 is a sectional view on the line $w-w$ of Fig. 9, Fig. 11 is a detail sectional view illustrating another modification 55 in the head of the brush.

In the drawing, 2 represents the handle

of the brush. This may be of any suitable material adapted for the purpose. At one end of the handle the longitudinal edges thereof are bent downwardly and inwardly, 63 forming flanges 3, between which is a recess 4 that is adapted to receive the brush back 5 in which the bristles 6 are mounted in any suitable way. A spring clip 7 is pivoted at 8 on the handle and has an end portion 9 that is adapted to engage the outer end of the brush back 5 and lock it in the recess. This clip may be swung to one side to allow the brush back 5 to be withdrawn from the flanges 3 and turned end for end therein, so 70 that when the bristles at one end of the brush become worn, the head may be reversed and the life of the brush thereby considerably prolonged. Furthermore, when the bristles become loose or worn out, a new 75 head may be substituted for the old one and a new brush thereby obtained without the necessity of throwing away the handle and purchasing an entirely new brush, as usually is necessary in devices of this kind. Instead 80 of providing the clip 7 on the handle, I may make the end of the handle convex, as indicated at 10 in Fig. 5, and provide inwardly curved, flanged edges 11 thereon, which, when separated by pressure on the curved 85 portion, will allow the insertion of the brush head between them and will grip the edges of the brush head when released and hold it securely in the handle without the necessity of any other fastening means. 90

In Figs. 6, 7 and 8 I have shown another modification, which consists in providing a brush head 12 having notches 13 in the ends thereof to receive bosses 14 pressed or punched from the end portion of the handle 95 and attached to said end portion by means of a centrally arranged pivot pin 15. This pivot pin is preferably in the form of a screw that is tapped at one end into the back of the brush 12 and has a bearing on 100 the handle 2. This screw may be readily removed at any time to allow substitution of one brush head for another, and it also allows the brush to be revolved on the handle and adjusted at any desired angle there- 105 to to reach any point on the inner or outer surfaces of the teeth, and when the bristles at the outer end of the brush are worn, the brush head may be turned end for end on its pivot, the boss 14 slipping into the re- 110 cess 13 and holding the brush head in alignment with the handle. When this construc-

tion is employed, I prefer to mount the brush head so that it will project about half of its length beyond the end of the handle, as shown in Fig. 7. The brush handle, or the part on which the brush head is mounted, is preferably composed of a yielding spring-like material which, when the brush is in use, will exert a yielding pressure on the brush head and cause the bristles to more thoroughly cover the tooth surface and thereby increase the efficiency of the brush. This springy nature of the handle, or the part which carries the brush head will allow the convenient insertion of the brush head and hold it securely in place.

In Figs. 9 and 10 I have shown another modification, which consists in a brush head 16 having beveled surfaces 17 which are adapted to engage similar surfaces provided on the flanged edges 18 of the handle. A pivot screw, similar to the one described, connects the middle portion of the brush head 16 with the handle and allows the brush head to be revolved to reverse it on the handle and the engagement of the beveled surfaces of the brush head and the flanges on the handle will operate to hold the head securely in alignment with the handle.

In Fig. 11 I have illustrated a conical recess 13' in the brush head that is adapted to receive a conical projection 14' that is pressed or punched out of the handle part 2. In other respects the mounting of the pivot screw is substantially the same as heretofore described.

The handle of the brush, and the part or holder in which the brush head is mounted, may be of any suitable material, and the size of the holder and the brush itself may be increased or decreased, and, if preferred,

the bristles at one end of the brush head may be made of a shape to fit the outer surface of the teeth, while those at another part of the head may be formed to fit the inner tooth surfaces. This, however, I regard as an immaterial modification, as the bristles may be varied in length or form and still be within the scope of my invention.

I may also apply this invention to other brushes, such as hair and clothes brushes or those used in manicuring.

I claim as my invention:—

1. A tooth brush comprising a handle provided with a flexible extension at one end and a boss formed thereon, a brush head centrally pivoted on said extension and adapted to be turned end for end on its pivot in alignment with said handle, said brush head having notches therein to receive said boss and adapted to be disengaged from said boss when lateral pressure is applied to said head.

2. A tooth brush comprising a handle provided with a flexible extension at one end, a brush head centrally pivoted on said extension and adapted to be turned end for end on its pivot in alignment with said handle, said extension and said brush head having means formed therein for interlocking and holding said brush head in alignment with said handle, lateral pressure upon said brush head disengaging said interlocking means.

In witness whereof, I have hereunto set my hand this 31st day of October 1913.

GAYLORD W. BEEBE.
